(57) **CLAIM**

The ornamental design for a rear bumper for an automobile, as shown and described.

DESCRIPTION

FIG. 1 is a perspective view of a rear bumper for an automobile showing my new design;

FIG. 2 is a front elevation view thereof;

FIG. 3 is a top plan view thereof; and,

FIG. 4 is a right side elevation view thereof.

The de-emphasized and halftone portions shown in the drawings illustrate environmental structure for a rear bumper for an automobile that form no part of the claimed design.
